US00D882882S

(12) **United States Design Patent** (10) Patent No.: **US D882,882 S**
MacNeil et al. (45) Date of Patent: ** Apr. 28, 2020

(54) **PET FEEDING SYSTEM**

- (71) Applicant: **MacNeil IP LLC**, Bolingbrook, IL (US)
(72) Inventors: **David F. MacNeil**, Fort Lauderdale, FL (US); **Frederick W. Masanek, Jr.**, Barrington, IL (US)
(73) Assignee: **MACNEIL IP LLC**, Bolingbrook, IL (US)
(**) Term: **15 Years**
(21) Appl. No.: **29/701,920**
(22) Filed: **Aug. 15, 2019**

CLAIM

We claim the ornamental design for a pet feeding system, as shown and described.

DESCRIPTION

FIG. 1 is a top perspective view of a pet feeding system according to our design, shown in an assembled condition; FIG. 2 is an exploded top rear perspective view thereof; FIG. 3 is an exploded bottom perspective view thereof; FIG. 4 is a top view thereof; FIG. 5 is a front view thereof; FIG. 6 is a rear view thereof; FIG. 7 is a left side view thereof, a right side view being a mirror image of the view shown; FIG. 8 is a top perspective view of a mat used in the design shown in FIG. 1; FIG. 9 is a top view of the mat shown in FIG. 8; FIG. 10 is front view of the mat shown in FIG. 8; FIG. 11 is a rear view of the mat shown in FIG. 8; FIG. 12 is a left side view of the mat shown in FIG. 8, a right side view being a mirror image of the left side view; FIG. 13 is a side-to-side elevational sectional view taken substantially along line 13-13 of FIG. 8; FIG. 14 is a front-to-back elevational sectional view taken substantially along line 14-14 of FIG. 8; FIG. 15 is top perspective view of either of two bowls used in the design as shown in FIG. 1; FIG. 16 is a top view of the bowl shown in FIG. 15; FIG. 17 is a right side view of the bowl shown in FIG. 15, a left side view being a mirror image of the right side view; FIG. 18 is a rear view of the bowl shown in FIG. 15; FIG. 19 is a front view of the bowl shown in FIG. 15; FIG. 20 is a bottom view of the bowl shown in FIG. 15; FIG. 21 is a side-to-side sectional view taken substantially along line 21-21 of FIG. 16; and, FIG. 22 is a front-to-rear sectional view taken substantially along line 22-22 of FIG. 16.

The broken lines depict portions of the pet feeding system that form no part of the claimed design.
